(57) **CLAIM**

The ornamental design for a computer chassis, as shown and described.

DESCRIPTION

FIG. 1 is a top, front, left side perspective view of a computer chassis;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 shows the front view of FIG. 2 on an enlarged scale;

FIG. 9 shows the rear view of FIG. 3 on an enlarged scale;

FIG. 10 shows a dash-dot-dot rectangle identifying a portion of FIG. 8; and,

FIG. 11 shows the portion identified in FIG. 10 on a further enlarged scale.

The dot-dash broken lines in the figures represent boundaries of the claimed design and form no part thereof. The “11” and the associated dash-dot-dot line shown in FIG. 10, as well as the dash-dot-dot rectangle identifying and displaying the enlarged region, form no part of the claimed design. All other broken lines and surfaces without surface shading illustrate portions of the computer chassis that form no part of the claimed design.
